UNITED STATES PATENT OFFICE.

EARL C. HANSON, OF CHICAGO, ILLINOIS.

REPRODUCING APPARATUS FOR PHONOGRAHS AND THE LIKE.

Application filed January 19, 1926. Serial No. 82,246.

My invention relates broadly to apparatus for the reception and reproduction of sound modulated radio energy and more particularly to the use of such apparatus in connection with radio phonographs.

One of the objects of my invention is to provide an artistic apparatus which may form a part of the furnishing of a room in a home, a club, or other building and receive and reproduce news, music, sermons, lectures, entertainments, and grand opera, broadcasted by radio telephony.

Another object of my invention is to provide means for combining such a radio receiving equipment with the usual construction of phonograph.

A further object of my invention is to provide means for adapting the usual phonograph for producing an increased volume of sound by employing a thermionic vacuum tube amplifier introduced between the tone arm and the amplifying horn of a phonograph.

A still further object of the invention is to provide means in a unit apparatus for reproducing sound records as in the case of the present phonograph or for reproducing sound from the records at an increased volume by vacuum tube amplification or for utilizing the sound amplifying horn of a phonograph in association with the radio apparatus for directing the received radio signals to an audience.

A still further object of the invention is to provide control means for modifying the volume of reproduced sound.

Other and further objects of my invention will be understood from the following specification and by examination of the accompanying drawings in which:

Fig. 1 is a form of radio phonograph employing an "Art Style" or "Period" case design cabinet in association with an antenna system concealed within a room decoration;

Fig. 2 is a fragmentary view of a part of the radio phonograph shown in Fig. 1 and the electrical connections employed therein.

The invention comprises broadly a phonograph cabinet which may if desired be of artistic design and which forms a part of the furnishing of a club or other building room of a home and includes within the cabinet the phonograph mechanism and a

radio receiving apparatus. A loop antenna is employed as a collector of radio wave energy.

The collector is connected to radio apparatus within the cabinet which may comprise a radio frequency vacuum tube amplifier, a vacuum tube detector and an audio frequency vacuum tube amplifier having a loud speaking telephone connected in its output circuit. The telephone receiver is arranged to direct the reproduced sound thru the sound amplifying horn of the phonograph. Means is provided for controlling the volume of reproduced sound. The radio phonograph may also include a vacuum tube amplifier which may be electrically connected between the tone arm and the sound amplifying horn by which the sound may be reproduced at increased volume. The phonograph may also be operated at increased volume. The phonograph may be also operated normally and independently of the vacuum tube amplifier or radio receiver. Circuits are provided whereby the energy received thru the radio apparatus may be amplified by the vacuum tube amplifier and the received signals directed thru the sound amplifying horn. The radio wave energy collecting means may be of any type such as the resonant coil, open antenna and ground or counterpoise underground antenna or loop collector.

Fig. 1 represents a form of radio phonograph in which an Art Style or Period case design cabinet 45 is employed as an enclosure for a phonograph or a radio receiving installation. The cabinet is arranged in different sections as for example, the phonograph is contained in section 47 and the radio receiver with the thermionic vacuum tube amplifier in section 46, while the batteries for supplying the plate potential for the thermionic vacuum tubes and the storage battery with rectifier for supplying the filament heating current are contained in section 48. Connections 50 and 51 are provided upon the cabinet for connection to any form of radio wave energy collector. The particular form shown comprises a loop collector 52, which is mounted within and concealed by the floor lamp 53. This form of antenna has been selected by reason of its attractive appearance in association with the Art Style or Period case design apparatus. The loop 52 is mounted within the lamp

shade 55, and is adapted to be rotated to secure the desired position relative to the distant broadcasting station. The leads from the ends of the loop may be taken through the pedestal of the lamp as indicated at 54 and provided with terminals which are connected through flexible conductors with the terminals 50 and 51 of the Period Style cabinet. This arrangement of equipment produces a pleasing effect for a resident installation.

The mechanical arrangement and electrical wiring of the radio phonograph represented in Fig. 1 is illustrated in Fig. 2. The 15 phonograph is represented at 47 including the rotating record table 61 and sound box 62 secured upon tone arm 63. The tone arm is swivelled at 64 to permit movement of the stylus over the phonograph record. The 20 tone arm connects to a casting 65 which is positioned between the sound amplifying horn 76 and the swivelled portion of the tone arm. The phonograph as thus far described operates in the usual manner independently 25 of any other equipment in the cabinet.

The casting 65 is provided with a connection to a telephone transmitter 68. This transmitter receives the sound vibrations conveyed through the tone arm 63. The transmitter 30 is electrically connected by conductors 69 through battery 71 with primary winding 70 of a transformer. The secondary winding 72 is connected to terminals of a double pole double throw switch 60. The switch blades 35 are connected to the input circuit of a vacuum tube amplifier including the thermionic vacuum tube 74. The output circuit of the amplifier includes the loud speaker telephone receiver 75. The telephone receiver 75 is 40 secured to the casting 65 and is arranged to direct the reproduced sound through the sound amplifying horn 76. Within the casting 65 and intermediate the mechanical mountings of the telephone transmitter 68 and the telephone receiver 75 is provided 45 a butterfly valve 66. The butterfly valve is rotatable by means of control 67 and in its horizontal position cuts off the acoustic connection between the sound box 62 and the 50 sound amplifying horn 76. In the vertical position of the butterfly valve the sound passes from the sound box to the sound amplifying horn without obstruction. The butterfly valve is normally in the vertical position 55 when the phonograph is employed independently of the other apparatus in the cabinet.

When it is desired to reproduce the sound at increased volume, the butterfly valve 66 is rotated to a horizontal position and switch 60 is thrown to the right completing the circuit from the telephone transmitter 68 through the transformer 70 and 72 and through the vacuum tube amplifier represented at 74. The loud speaker telephone 65

receiver 75 directs the music or other sounds at large volume into the amplifying horn 76.

The cabinet is employed as a reproducer of the received radio signals when the switch 60 is thrown to the left contacting with terminals 59^a and 59^b. These terminals are connected to the secondary winding 59 of a transformer 58. The primary winding 57 of the transformer 58 connects to terminals 41 and 42 which are the terminals of the 75 output circuit of the receiving apparatus.

With the switch thrown to the left the energy received by radio is conveyed through amplifier 74 and actuates the loud speaking telephone receiver 75 directing the reproduced sound through the sound amplifying horn 76. During the operation of the apparatus as a reproducer of received radio signals, the stylus upon the sound box 62 is removed from the phonograph record and the butterfly valve 66 is arranged in a horizontal position.

What I claim is:

1. In an apparatus for the reproduction of sound the combination of a cabinet, a phonograph having a tone arm and a sound amplifying horn, apparatus in said cabinet for receiving radio signals, a vacuum tube amplifier, means associated with said phonograph and electrically connected with said amplifier for reproducing sound at large volume, means for directly conveying sound reproduced by said phonographs through said sound amplifying horn, and additional means whereby radio signals are amplified, reproduced, and conveyed through said sound amplifying horn.

2. In an apparatus for the reproduction of sound the combination of a cabinet, a phonograph having a tone arm and a sound amplifying horn therein, a radio receiving apparatus, an amplifier, means for supplying power to the circuits of said amplifier, means for alternately operating said phonograph independently and in combination with said amplifier, and means for conveying received radio signals through said sound amplifying horn.

3. In an apparatus for the reproduction of sound the combination of a cabinet, a phonograph having a tone arm and a sound amplifying horn, apparatus for receiving radio signals, a vacuum tube amplifier, electrical means associated with said phonograph and said amplifier whereby sound may be reproduced in association with or independently of said amplifier, and means whereby signals received by said radio apparatus may be conveyed through said sound amplifying horn.

4. In an apparatus for the reproduction of sound the combination of a cabinet, a phonograph having a tone arm and a sound amplifying horn therein, a radio receiving apparatus in said cabinet, a vacuum tube

- amplifier, means between said tone arm and said sound amplifying horn for conveying sound from said phonograph, actuating said amplifier and reproducing same through said sound amplifying horn, and means independent of said phonograph for conveying received radio signals through said amplifier and said sound amplifying horn.
5. In an apparatus for the reproduction of sound the combination of a cabinet, a phonograph having a tone arm and a sound amplifying horn, a radio receiving apparatus, a vacuum tube amplifier, mechanical means between said tone arm and said sound amplifying horn for conveying sound from said phonograph directly to said sound amplifying horn, means for converting sound from said phonograph into electrical energy, amplifying said energy and reproducing same through said sound amplifying horn, and means for conveying received radio signals through said amplifier and sound amplifying horn.
10. In an apparatus for the reproduction of sound the combination of a cabinet, a phonograph having a tone arm and a sound amplifying horn, a radio receiving apparatus, a vacuum tube amplifier, means between said tone arm and said sound amplifying horn for alternately conveying reproduced sound directly into said amplifying horn and converting the sound into electrical energy and conveying said energy through said amplifier and said sound amplifying horn, and means for conveying received radio signals through said amplifier and through said sound amplifying horn.
15. In an apparatus for the reproduction of sound the combination of a cabinet, a phonograph in one of said compartments, a radio receiving apparatus in another of said compartments, a vacuum tube amplifier in one of said compartments, a source of electric energy in another of said compartments, a sound amplifying horn in another of said compartments, and means whereby said phonograph may operate independently of or in combination with said vacuum tube amplifier to convey sound through said sound amplifying horn and means whereby signals received by said radio apparatus may be conveyed through said sound amplifying horn.
20. In an apparatus for the reproduction of sound, the combination of a phonograph having a sound reproducing device and a sound amplifying device, apparatus for receiving radio signals, a vacuum tube amplifier, electrical means associated with said phonograph and said amplifier whereby sound may be reproduced in association with or independently of said amplifier, and means whereby signals received by said radio apparatus may be conveyed through said sound amplifying device.
25. In an apparatus for the reproduction of sound, the combination of a phonograph having a sound reproducing means and a sound amplifying device, apparatus for receiving radio signals, a vacuum tube amplifier, means associated with said phonograph and electrically connected with said amplifier for reproducing sound at large volume, means for directly conveying sound reproduced by said phonograph thru said sound amplifying device, and additional means whereby radio signals are amplified, reproduced, and conveyed thru said sound amplifying device.
30. In an apparatus for the reproduction of sound, the combination of a cabinet, a phonograph having a reproducing device and a sound amplifying device, apparatus for receiving radio signals, a vacuum tube amplifier, electrical means associated with said phonograph and said amplifier whereby sound may be reproduced in association with or independently of said amplifier, and means whereby signals received by said radio apparatus may be amplified through said sound amplifying device.
35. In an apparatus for the reproduction of sound, a phonograph having reproducing means and a sound amplifying device, radio signal receiving apparatus, a vacuum tube amplifier, and mechanism for causing the sound from said reproducing means to be amplified by said amplifier and delivered to said device at times, and at other times for causing the signals from said radio apparatus to be amplified by said amplifier and delivered to said device, said mechanism including means for directly conveying sound from said reproducing means to said device independently of said amplifier.
40. In an apparatus for the reproduction of sound, the combination of a cabinet, a plurality of compartments in said cabinet, a phonograph in one of said compartments, a radio receiving apparatus in another of said compartments, a vacuum tube amplifier in one of said compartments, a source of electric energy in another of said compartments, a sound amplifying horn in another of said compartments, and means whereby said phonograph may operate independently of or in combination with said vacuum tube amplifier to convey sound through said sound amplifying horn and means whereby signals received by said radio apparatus may be conveyed through said sound amplifying horn.
45. In an apparatus for the reproduction of sound, the combination of a cabinet, a plurality of compartments in said cabinet, a phonograph in one of said compartments, a radio receiving apparatus in another of said compartments, a vacuum tube amplifier in one of said compartments, a source of electric energy in another of said compartments, a sound amplifying horn in another of said compartments, and means whereby said phonograph may operate independently of or in combination with said vacuum tube amplifier to convey sound through said sound amplifying horn and means whereby signals received by said radio apparatus may be conveyed through said sound amplifying horn.
50. In an apparatus for the reproduction of sound, the combination of a cabinet, a plurality of compartments in said cabinet, a phonograph in one of said compartments, a radio receiving apparatus in another of said compartments, a vacuum tube amplifier in one of said compartments, a source of electric energy in another of said compartments, a sound amplifying horn in another of said compartments, and means whereby said phonograph may operate independently of or in combination with said vacuum tube amplifier to convey sound through said sound amplifying horn and means whereby signals received by said radio apparatus may be conveyed through said sound amplifying horn.
55. In an apparatus for the reproduction of sound, the combination of a phonograph having a sound reproducing device and a sound amplifying device, apparatus for receiving radio signals, a vacuum tube amplifier, electrical means associated with said phonograph and said amplifier whereby sound may be reproduced in association with or independently of said amplifier, and means whereby signals received by said radio apparatus may be conveyed through said sound amplifying device.

In testimony whereof, I have signed my name to this specification.

EARL C. HANSON.
